[57] CLAIM

The ornamental design for a helmet face shield, as shown and described.

DESCRIPTION

FIG. 1 is a right front oblique perspective view of a helmet face shield according to the present invention; FIG. 2 is a right side elevational view of the helmet face shield, the left side elevation being the mirror image of FIG. 2;

FIG. 3 is a front elevational view of the helmet face shield;

FIG. 4 is a rear elevational view of the helmet face shield;

FIG. 5 is a top plan view of the helmet face shield;

FIG. 6 is a bottom plan view of the helmet face shield; and,

FIG. 7 is a right front oblique perspective view of the helmet face shield in a raised position.

The broken line showing of a helmet in FIGS. 1, 2 and 7 is for illustrative purposes only and forms no part of the claimed design.

FIG. 1

FIG. 2.

FIG. 3

FIG. 4

FIG. 5.

FIG. 6.

FIG. 2.
